TAILLESS KITE

Hing F. Chu and Helga M. Chu, Larchmont, N. Y.

Application May 17, 1945, Serial No. 594,316

6 Claims. (Cl. 244—153)

1

This invention relates to a kite and it is one object of the invention to provide a kite having a frame and a plurality of wings which are disposed one above another and are so formed that they provide pockets adapted to be filled with wind and so balance the kite that use of a tail will be unnecessary.

Another object of the invention is to so form the wings that they extend transversely of the kite, certain of the wings being tapered from their ends towards the center of the kite and others being of the same depth from end to end and disposed in alternate relation to the tapered wings.

Another object of the invention is to provide a kite having a knock-down frame formed of sticks which are disposed in crossed relation to each other when assembled and secured by clips which engage about crossed portions of the sticks and firmly hold the crossed sticks together.

Another object of the invention is to so form the wings that they are provided with marginal seams or pockets through which cords pass with end portions of the cords protruding from the pockets and adapted to be tied about the sticks to firmly hold the wings to the sticks.

Another object of the invention is to provide the wings with an arrangement of seams or pockets through which the sticks are passed so that the wings will be held to the sticks along lines spaced from each other and portions of the wings between the sticks allowed to flex and form wind-receiving pockets.

Another object of the invention is to so form the kite that it may be flown with a single-string or double-string bridle and a number of kites connected with a main string in such manner that they will not interfere with each other.

Another object of the invention is to provide a kite so constructed that it will be sturdy when assembled for use but capable of being easily and quickly taken apart for storage when not in use.

The invention is illustrated in the accompanying drawing wherein:

Figure 1 is a view looking at the wings from the front.

Figure 2 is a rear view of the wings and showing the wings connected with each other.

Figure 3 is a rear view of the assembled kite.

Figure 4 is a front view of the assembled kite.

Figure 5 is a perspective view upon an enlarged scale showing crossed sticks connected with each other by a wire clip.

Figure 6 is a diagrammatic view of the strings used for flying a number of the improved kites.

2

This improved kite has a frame consisting of a center stick 1, side sticks 2, and a plurality of cross sticks 3 which are spaced from each other longitudinally of the center stick and the side sticks and disposed in crossed relation thereto with their ends projecting outwardly from the side sticks. These sticks may be formed of wood or other suitable material and at their points of crossing are held in engagement with each other by clamps or clips 4 formed of wire strands. The wire strands are resilient and each is bent to form a clip of double U-shaped formation having side bars 5 and bridging bars 6, one of the bridging bars being formed by end portions of the strand which are disposed in overlapping relation to each other and in a common plane so that they both bear against the stick across which they extend. It should also be noted that one end portion of the strand is bent to form a finger 6' 15 for engaging a side face of the stick when the clip is applied to the sticks. Referring to Figure 5, it will be seen that the clip or clamp has its bars 5 extending along side faces of the crossed sticks and that other side faces of the sticks are engaged by the bridges 6 which extend at right angles to the side bars 5. Therefore, the crossed sticks will be tightly gripped and firmly held in contacting engagement with each other.

The cover is shown in Figures 1 and 2 and referring to these figures, it will be seen that the cover consists of triangular upper and lower wings 7 and 8 and intermediate wings 9 and 10, the wing 9 being of the same height throughout its length, and wings 10 being tapered from their ends towards the vertical center of the kite. While a single wing 9 has been shown in the form illustrated, it will be understood that additional intermediate wings may be provided, according to the size of the kite and that the wings 9 and 10 will be alternately arranged when setting them in place between the end wings 7 and 8. Hems 11 are formed along margins of the wings and through these hems are passed strings 12 which have end portions protruding from the hems so that when the kite is assembled, the strings may be tied to the sticks as shown in Figures 3 and 4, the knots being bow knots so that they may be readily untied when the kite is to be taken apart for storage in a small space or receptacle after being used. Strips 13 are sewed to rear faces of the wings along transverse marginal edges thereof and form pockets to receive the cross sticks 3, and similar strips 14 are sewed vertically against the rear faces of the wings to form pockets through which the center stick 1 passes, it being

noted that the wing 9 has its upper and lower edges formed with notches or recesses 15 so that the center stick may be passed through openings formed by these recesses and have its intermediate portion disposed in front of the center wing 9 as shown in Figure 4. Therefore, the united wings will be held against the sticks and prevented from being blown forwardly away from the sticks. This eliminates likelihood of tearing the wings which may be formed of paper or thin fabric such as silk. After the sticks have been passed through the pockets formed by the strips 13 and 14, the clips 4 are applied and the strings then tied to the sticks. The cross sticks are so spaced from each other that the wings will be baggy between the sticks and since the wings 10 taper from their ends towards the center stick 1 and the wing 9 is of the same height throughout its length, the portions of the wings at opposite sides of the center stick 1, when subjected to pressure of wing, will balance each other and cause the kite to fly properly without a tail being necessary. A string 16 is used when flying the kite and this may be directly connected with the kite by tying through a small hole 17 near the center of the stick 1 or the string may be connected with a bridle 18 having its ends connected with the center stick in spaced relation to upper and lower ends thereof, as shown in Figure 4. In Figure 6, there has been shown an arrangement of strings including a main string 19 having auxiliary strings 20 leading therefrom for connection with bridles of a number of kites to be flown at the same time.

Having thus described the invention, what is claimed is:

1. In a kite, a frame including a center stick, side sticks, and cross sticks disposed in crossed relation to the center stick and the side sticks, clamps removably holding the cross sticks in engagement with the center stick and the side sticks, each clamp consisting of a wire strand bent to form U-shaped jaws disposed transversely of each other and adapted to straddle and grip the crossed sticks, and a cover for said frame having edge portions formed with seams, and strings in said seams having end portions protruding from ends of the seams and tied about the sticks to removably hold the cover to the sticks.

2. In a kite, a frame including a center stick, side sticks, and cross sticks mounted in crossed engagement with the center stick and the side sticks, and a cover for said frame including transversely extending intermediate sections and upper and lower sections, one of the intermediate

sections being of even height throughout its length and disposed between intermediate sections tapered from their ends towards the center stick, strips connecting adjoining edges of said sections and forming pockets through which the cross sticks pass, other strips mounted vertically midway the length of the sections and through which the center stick passes, the center section being formed with openings through which the center stick passes, and strings mounted along edges of said sections with end portions protruding therefrom and releasably tied to the sticks.

3. In a kite, a frame including longitudinally extending sticks and cross sticks mounted in crossed relation to the longitudinally extending sticks, and a cover for said frame releasably secured to the sticks and consisting of upper and lower sections and intermediate sections, certain of the intermediate sections being of an even height throughout the width of the cover and disposed between other intermediate sections tapered from their ends, the cover being loosely applied to the frame and its intermediate sections forming wind-receiving pockets cooperating with each other to balance the kite when in flight.

4. In a kite, a frame including a center stick and cross sticks extending across the center stick, a cover for said frame having upper and lower sections, a center section, and intermediate sections between the center section and the upper and lower sections, the center section being of an even depth throughout the width of the cover, and the intermediate sections being tapered from their ends towards the center stick.

5. In a kite, a frame including a center stick and cross sticks mounted across the center stick, a cover for said frame having upper and lower sections and intermediate sections, pockets being formed along adjoining edges of said sections through which the cross sticks pass, the center one of the intermediate section forming a wind pocket of an even depth throughout the width of the cover, and the intermediate sections above and below the last mentioned section forming wind pockets tapered from opposite side edges of the cover towards the center stick.

6. In a kite a frame, and a cover for said frame, including upper and lower sections and intermediate sections, said intermediate sections being baggy, certain of the intermediate sections forming a wind pocket of an even depth throughout the width of the cover and disposed between sections tapered from opposite side edges of the cover to form conical wind pockets.
